Primary Examiner — Ian Simmons*Assistant Examiner* — Shannon Weekley*(74) Attorney, Agent, or Firm* — Fish & Richardson P.C.(57) **CLAIM**

The ornamental design for a cake pop mold, substantially as shown and described.

DESCRIPTION

FIG. 1 is a perspective view of the cake pop mold in a closed position;

FIG. 2 is a front view of the cake pop mold in the closed position;

FIG. 3 is a back view of the cake pop mold in the closed position;

FIG. 4 is a right side view of the cake pop mold in the closed position;

FIG. 5 is a left side view of the cake pop mold in the closed position;

FIG. 6 is a top view of the cake pop mold in the closed position;

FIG. 7 is a bottom view of the cake pop mold in the closed position; and,

FIG. 8 is a perspective view of the cake pop mold in a partially open position.

1 Claim, 4 Drawing Sheets# US D684,019 S
